(57) **CLAIM**

The ornamental design for a display and mask for a gaming device, as shown and described.

DESCRIPTION

This application is related to the following commonly-owned co-pending design and utility patent applications: "Display and Mask for a Gaming Device," Ser. No. 29/130, 997, "Display and Mask for a Gaming Device," Ser. No. 29/131,001, "Player Interface and Tray for a Gaming Device," Ser. No. 29/130,983, "Tray for A Gaming Device," Ser. No. 29/130,981, "Player Interface With Bolster for a Gaming Device," Ser. No. 29/130,980, "Plate for Midsection of a Gaming Device," Ser. No. 29/130,992, "Top Unit and Base for a Gaming Device," Ser. No. 29/130,979, "Base for a Top Unit of a Gaming Device," Ser. No. 29/130,982, "Gaming Device," Ser. No. 29/130,996, and "Translucent Monitor Masks, Substrate and Apparatus for Removable Attachment to a Gaming Device Cabinet," Ser. No. 09/686, 243.

FIG. 1 is a front perspective view of a gaming device showing a display and masks of our new design, that portion of the gaming device shown in phantom is not part of the design sought to be patented and is provided for environmental purposes only;

FIG. 2 is a top plan view thereof;

FIG. 3 is a left side elevational view thereof, the right side being a mirror image thereof; and,

FIG. 4 is a front elevational view, showing the display and mask of our design.
